UNITED STATES PATENT OFFICE.

ROBERT BRUCE EMERSON, OF WASHINGTON, DISTRICT OF COLUMBIA,
ASSIGNOR TO THE EMERSON STEAM PUMP COMPANY, OF ALEX-
ANDRIA, VIRGINIA, A CORPORATION OF VIRGINIA.

STEAM VACUUM-PUMP.

SPECIFICATION forming part of Letters Patent No. 773,133, dated October 25, 1904.

Application filed November 18, 1902. Serial No. 131,854. (No model.)

To all whom it may concern.

Be it known that I, ROBERT BRUCE EMERSON, of Washington, District of Columbia, have invented certain new and useful Improvements 5 in Steam Vacuum-Pumps; and I do hereby declare the following to be a full, clear, and exact description of the same, reference being had to the accompanying drawings, forming a part of this specification, and to the letters of reference marked thereon.

This invention relates to steam vacuum-pumps, the improvements being particularly, though not exclusively, applicable to those pumps in which steam acts directly on the 15 surface of or against a body of water in a suitable receiver or chamber to displace the same and is itself then condensed, creating a vacuum to effect the inspiration of a new charge or body of water, the direction of the 20 flow of the water and the admission of the steam being controlled by suitable valves and operating means therefor.

Some of the objects of the present invention are to provide a pumping mechanism of 25 extreme simplicity, light in weight, but of great strength and capacity for a given size.

Further objects of the invention are to provide an apparatus having the above characteristics and which shall be absolutely reliable 30 and capable of ready regulation under any and all the unfavorable conditions to which this class of apparatus is subjected in use, and particularly in mine-pumping, where continuous service is required regardless of the 35 conditions, such as gritty, muddy, or acid conditions of the water or of the accumulation of dirt and debris on the exposed portions of the pump.

A further object of the invention is to provide a pumping apparatus of the character mentioned which shall have a wide range of adaptability, permitting of effective and economical installation under widely different conditions, but without the necessity of changing the working parts further than is occasioned by variations in assembling the same. For instance, according to the present invention while the chambers, or, as they will be

termed herein, the "cylinders," and the mechanism for controlling the steam thereto are 50 usually assembled in close proximity, yet they may be widely separated, the cylinder or cylinders being located, say, at the bottom of a shaft, while the entire steam-controlling mechanism may be at the top of the shaft or even 55 in the boiler-house away from the top of the shaft without in any wise interfering with the automatic and efficient running of the apparatus.

The invention may be carried into effect 60 with a single cylinder or chamber; but a plurality of cylinders or chambers are preferably employed and will be described herein; but it is not intended thereby to limit the invention to such construction, the invention consisting more particularly in the mechanism for controlling the flow of the steam and water, although the multiplication of the cylinder is followed by advantages, inasmuch as a single steam-controlling mechanism may be 70 employed for all the cylinders.

The invention further consists in certain novel details of construction and combinations and arrangements of parts, all as will be now described, and pointed out particularly 75 in the appended claims.

Referring to the accompanying drawings, Figure 1 is a front elevation of a pump embodying the present improvements with portions broken away. Fig. 2 is a top plan view 80 of the same with some of the pipe connections omitted. Fig. 3 is a rear, and Fig. 4 a side, elevation, portions being broken away in both views. Fig. 5 is a horizontal section on the line 5 5, Fig. 3, looking down. Figs. 6 and 85 7 are vertical sections on the lines 6 6 and 7 7, Fig. 5. Fig. 8 is a view showing in elevation the several parts of the valve mechanism for controlling the steam-supply, together with associated parts, including the engine, the 90 several members being drawn apart in order that the construction of each may be understood. Fig. 9 is a top plan view of the body of the valve-fitting with the cap removed and the valve and its operating-gearing partially 95 broken away. Fig. 10 is a plan of the valve

and also showing the position of the ports with relation thereto. Fig. 11 is a plan of the bottom head of the engine-casing. Fig. 12 is a bottom plan of the engine-valve. Fig. 13 is a detail of one of the condenser-sprayers. Fig. 14 is a detail elevation illustrating one way in which the valve and its operating mechanism may be mounted remote from the body of the cylinders. Fig. 15 is a vertical section through a valve-fitting with a modified form of valve and change gearing for driving the same. Fig. 16 is a plan of the valve Fig. 15. Fig. 17 is a section through the water-discharge pipe and steam-pipes, where the cylinders and valve mechanism are separated widely to show a means for supporting and bracing the pipes. Fig. 18 is a section on the line 18 18, Fig. 4.

Like letters of reference in the several figures indicate the same parts.

In the preferred type of apparatus and which is the type illustrated herein twin chambers or cylinders A are employed, said cylinders being relatively long and arranged side by side in vertical position or so as to take from a common bottom supply. The cylinders may be made in a single casting, and they are joined at one end only—for instance, as shown in the drawings, where they are joined at the bottom, and although in casting it may be convenient to form a web connecting them near the top, such web should be separated by a saw-kerf, as indicated at *a* in Fig. 3, in order that the cylinders may be free to expand and contract independently under variations in temperature. The web at *a* will, however, form a brace for properly spacing the cylinders.

Below the cylinders there is an intake or suction chamber formed by a base-casting A', secured in place by bolts and to the bottom of which the usual suction or supply pipe A² may be connected for supplying both cylinders.

In the bottom of each cylinder and between the same and the suction-chamber there is provided an intake-valve B. (Best shown in Figs. 6 and 7.) The valves may be of any ordinary construction; but in the preferred construction a removable valve-seat in the form of a grid B', having a peripheral flange *b*, adapted to seat against a suitable shoulder *b'* in the cylinder, is provided.

Between the flange and shoulder packing *b'* may be interposed and the valve-seat clamped down in place by a single central bolt B² passing up through the suction-chamber from the outside, where it is readily accessible. The valve itself may be a heavy rubber disk 60 mounted by a metal plate B³ and held down in place by a spring B⁴, confined between the valve and the enlarged head of a valve-stem B⁵, the end of the latter passing down through the valve and screwing into the central portion of the grid and preferably in the upper

portion of the threaded opening, which the bolt B² enters from the bottom. Access to the valves may be had through hand-holes or openings normally closed by the covers A³.

Leading from each of the cylinders near the bottom is a discharge-passage A⁴, Fig. 7, said passage merging in a common discharge-chamber A⁵, from which the discharge-pipe A⁶, Figs. 3 and 4, leads to any point desired. In each of the discharge-passages and between the cylinder and the discharge-chamber there is interposed a discharge-valve C, the construction of which, together with its associated parts, is similar to that of the valve B, and hence will not need specific description. The bolt C², however, which corresponds to the bolt B², passes in from the bottom of the lateral projection of the casting which forms the passage A⁴ and chamber A⁵ and is in position to be readily tightened or loosened from the outside. Access may be had to the valves C through a hand-hole or opening in the face of the discharge-chamber, which opening is normally closed by a cap or cover C'. The discharge passages and chamber are preferably formed in the casting connecting the two cylinders, as will be readily understood from Figs. 5, 6, and 7, the discharge-chamber thus forming a connection between the discharge of the two cylinders and avoiding all joints and packings such as would be liable to leak or loosen up under severe strains at the point where such strains are manifest.

At their upper ends the cylinders are preferably tapered toward the steam-inlet, as shown at A⁷, to form a stronger structure and reduce the area on which the steam first acts, the latter being especially important in that it presents a less area in which the surface of the water can be agitated, and therefore reduces the steam condensation in the initial stages of the expiration cycle and also reduces the clearance should the cylinders not quite fill. The effect of the reduction in the area is to quickly calm the surface of the water, and in order to still further increase this effect it is found desirable in some instances, particularly where the cylinders are of large diameter, to introduce partitions or walls extending lengthwise of the cylinder. Such partitions or walls are shown at A⁸ in Figs. 4 and 18, and it is obvious that any number may be employed and that they may be of any preferred form to reduce the continuous area of the surface of the water. They extend as far as desired lengthwise of the cylinders, although in practice it is found that they need only be located at the extreme upper end, as shown by the dotted lines in said Fig. 4.

Jug-handles A⁹ are preferably formed integral with the upper ends of the cylinders, by which the apparatus may be suspended or hoisted without straining any of the connections.

The upper ends of the cylinders are formed

for the attachment of the steam connections, for which purpose cap-plates D are bolted thereto, said plates having central apertures for the steam connections and baffle-plates D', Fig. 8, suspended immediately below said apertures to break the direct impact of the steam against the water and to distribute the same evenly in the upper end of the cylinders.

The valve for controlling the admission of steam to the cylinders and the mechanism for operating the same are self-contained, and all moving parts are incased, so as to be entirely removed from danger of injury or clogging by dirt, debris, or accumulations, and hence 15 may be directly attached to the upper ends of the cylinders; but it may be and frequently is more desirable to locate the valve and its operating mechanism remote from the cylinders—for instance, in the boiler-house or at 20 the top of a shaft—whereas the cylinders must be at the bottom of the shaft, and it may be under conditions, such as submergence, which would preclude access to the valve mechanism for starting, stopping, or varying the speed 25 of operation, and the present structure is well adapted for such situations by simply lengthening the steam-pipe connections leading to the top of the cylinders—as shown, for instance, in Fig. 14, where the pipes F may be 30 made as long as desired and extended to any desired situation.

The mechanism referred to for controlling the admission of steam to the cylinders embodies a fitting forming a steam-chamber, into 35 which steam is admitted from any suitable source through a pipe G, having a throttle or gate valve G' for regulating the quantity of steam admitted, said fitting having two passages leading from said chamber, one to each 40 of the cylinders, and a valve for controlling the admission of steam to said passages and adapted to be controlled by an engine preferably connected with and, in effect, forming a part of the fitting.

45 The steam-pipe G enters a cap H, which for convenience in manufacture is recessed on the under side to form the steam-chamber, as indicated in dotted lines, Fig. 8, and the cap fits down on the body portion I of the fitting. 50 The body portion I has two laterally-extending arms I', Fig. 9, with the steam-passages therein leading to the cylinders, said passages at their inner ends forming ports i and at their outer ends forming sockets i', Fig. 8, in 55 which rounded nipples d' on connections D are adapted to seat, forming a universal joint. The body of the fitting and cylinder connection are secured together to form a steam-tight joint between the nipple and its socket 60 by bolts K passing down through lugs I² on the body-fitting and into the cylinder connections, said bolts being disposed at diametrically opposite points with respect to the nipples and the bolts on one side being preferably arranged parallel with those on the other, 65

whereby a certain degree of flexibility in the connection between the parts is allowed, and one cylinder may elongate or contract independently of the other without opening a joint or straining any of the parts, as would 70 be the case if all were rigid and inflexibly connected. Obviously other forms of flexible joint may be substituted between the cylinders.

The valve for controlling the passage of 75 steam through the ports i is preferably a flat rotary valve L, Figs. 8 and 10. To form an effective seat for this valve and one which may be dressed accurately and yet not cause friction or undue wear, the wall of the ports 80 i is raised slightly, as at i², and the valve rests and takes its bearing thereon and on a peripheral bearing portion i³, Figs. 8 and 9, of corresponding height, but portions of which may be removed to reduce frictional and unbalanced area. Steam is free to pass under the valve through its open portion; but owing to the ports and bearing-surfaces there is a sufficient preponderance of pressure above 85 the valve to insure its being held to its seat 90 without creating undue friction and wear.

Passing up vertically from the bottom of the fitting is a valve-operating shaft M, said shaft being a continuation of the engine crank-shaft M', as will presently appear; and suitable 95 gearing is interposed between the shaft and the valve to rotate the latter from the former, but at a reduced speed. Any ordinary or desired speed-reducing gear may be employed, a simple form being adopted for illustration 100 in Figs. 8, 9, and 10, consisting of a small gear or pinion m, into which the shaft screws, a second larger gear m', journaled on a stud, axle, or pin m² in the cap and meshing on one side with said pinion and on the opposite side 105 with an internal gear m³ on or forming a part of the valve L. The larger gear m' may rest directly on the valve, for which purpose the valve may be formed with a shroud m⁴, extending around the steam-opening L'. 110

The lower face of the body-fitting I is in the form of a flange O and central projection o, adapted to constitute the top head or end of the engine-casing. The engine, so far as the cylinders and casing are concerned, is of 115 the ordinary multiple or three-cylinder type to avoid dead-centers, the casing P and cylinders P' being preferably in one casting, and the casing is secured by bolts to the face of the flange O, with the projection o in the central opening of the casing and the crank M' 120 in position for the connecting-rods of the pistons to coöperate therewith.

The lower end of the engine-casing is closed by a head or cap P², having a central projection p², corresponding to the projection o. As a convenient and cheap construction which will cause the engine and valve L to move in accord a valve for the engine is provided, which is moved by the crank M', and the en- 130

gine-casing constitutes a steam-chamber from which the steam is distributed to the several cylinders. The engine-valve is a flat rotary valve R, Figs. 8 and 12, having a central boss r' fitting in an opening r' , Fig. 11, in the bottom head r^2 , said opening also constituting the exhaust-duct, as will presently appear.

Passages r^2 are formed in the cylinder-walls leading from the outer ends of the cylinders 10 into a convenient point for registry with corresponding passages r^3 in the head P^2 , and the latter passages terminate in ports r^4 beneath the valve R. Valve R has an arc-shaped groove R' in its under face opening into the 15 central opening r' of the head and constituting the exhaust-passage. The under face of the valve is cut away at R^2 to form a live-steam space or passage, and the steam is admitted around the periphery of the valve. 20 Steam may thus pass from the center of the casing through the cut-away portion of the valve to the ports leading to the outer ends of some of the cylinders and from the others to the exhaust, the parts, as shown, being so 25 proportioned that steam is admitted and exhausted to cause a rotation of the shaft in one direction. Motion is imparted to the valve from the crank M' , for which purpose the said valve is recessed, as shown by the dotted lines 30 at r^5 , Fig. 12, and in full lines, Fig. 8, for the reception of the end of the crank, and the preponderance of pressure being in the engine-casing and above the valve it will be held to its seat by steam-pressure and without the use 35 of springs or packings.

Inasmuch as the shaft M extends from one live-steam chamber to another, no packing is necessary around the same, although it is desirable that the shaft should have a reasonably 40 accurate fit in its bearings, because it is desirable under some circumstances to have a different pressure in the steam-chamber of the pump from that in the steam-chamber of the engine-cylinders. Thus where low pressure is desired in the cylinders it is not desirable to cut down the pressure for operating 45 the engine and valve, and vice versa. The engine-supply is consequently preferably taken from the main steam-pipe at a point 50 above the throttle-valve through a pipe S, which may also have a control-valve S' therein for regulating the engine by controlling the steam-supply thereto.

The preferred method of controlling the engine is by throttling its exhaust, and to permit this to be done conveniently an exhaust-pipe T is connected with the opening in the lower head of the engine-casing, and said pipe preferably extends down and opens into the 55 suction-chamber, which acts as a condenser, for there is always a minus pressure in said chamber, save when it is actually submerged. By this construction the escape of steam into the air is entirely avoided, and no exhaust-pipe 60 to carry the same away, as out of an inner

shaft, is necessary. The exhaust-pipe may, however, open directly into the air, or it may have a branch T', which does open directly into the air, both the main and branch pipes being provided with manually-controllable valves t and t' , respectively, whereby the exhaust may be accurately controlled and the speed of the engine regulated. 70

Water for effecting the condensation of the steam in each cylinder after the discharge of the water is admitted to the cylinder through spray-nozzles U, the inner ends of which turn upwardly, so as to prevent drip, and the spraying is preferably effected by splitting the column of water discharged through the nozzle by a wedge-shape blade u , preferably formed as a part of the nozzle and held at the proper point above the same by supports at each end, although any form of nozzle may be substituted. The body of the nozzle is 80 somewhat enlarged and provided with threads at U', whereby it may be inserted from the outside and screwed directly into the wall of the cylinder. Outside of the threaded portion just mentioned the nozzle is formed for the attachment of a pipe U^2 , which leads to the bottom of the adjacent cylinder, this being a convenient source of condenser water-supply, and as the pressure in the cylinders alternates the water will be promptly injected 90 into the cylinders alternately. From the foregoing it will be understood that the condenser-pipe of each cylinder leads to the bottom of the other cylinder, and in order to facilitate the application and removal of said 100 pipes unions U^3 are introduced at each end, and in addition each pipe has a check-valve U^4 to prevent back pressure through the spray-nozzle and a hand-valve U^5 , by which the rate of flow through the pipe may be regulated or set for the conditions under which the 105 pump is working at the time.

The arrangement of the valve fitting with the engine directly below the same permits of a most convenient and effective assembling, for one of the engine-cylinders passes between the upper ends of the pump-cylinders, and the whole presents a most compact appearance, (see Fig. 2,) offering little chance for the accumulation of debris and occupying but little space, whereby the pump is particularly adapted for use where but little room is available and a large quantity of water is to be handled. 110

By reference to Figs. 15 and 16 it will be seen that the form of the valve controlling the admission of steam to the cylinders, as well as the change-gearing for driving the same from the engine crank-shaft, may be considerably modified. In said figures the valve W is a flat rotary valve, as in the former instance; but it is segmental in shape and is journaled on the engine-shaft M. Above the valve a pinion w is screwed on the shaft and meshes with a larger pinion or gear w' , journaled on a stud-axle w^2 , 125 130

carried by the valve itself. The pinion or gear w' meshes with an internal gear w^3 , formed on a ring w^4 , forming a continuation of the cap w^5 . The ring and cap correspond to the cap H , but are formed separately to facilitate the cutting of the gear-teeth. Any desired system of change-gears may be introduced between the engine-shaft and ring to reduce the speed of the valve to the desired point or to enable the speed of the engine to be increased without increasing the speed of the valve.

When the cylinders and valve mechanism are widely separated—as, for instance, where the cylinders are at the bottom of a shaft and the valve mechanism at the top, (see Fig. 14)—it is found desirable to brace the water-discharge pipe and steam connections from each other. In Fig. 17 a clamp-casting y , formed in sections and clamped to the pipes by bolts y' , is shown as a convenient means for accomplishing this end, and it will be understood that as many of these braces may be employed as is found necessary or desirable.

From the foregoing the operation of the pump will be readily understood and may be briefly stated as follows: The pump-cylinders are placed in such proximity to the water that the cylinders will be filled by atmospheric pressure when a vacuum is created by the condensation of steam in the cylinders, the steam-valve and engine are set to admit steam to the cylinders alternately and preferably in such time that each cylinder may have received its full charge of water at the moment when the steam is admitted thereto, and in the preferred arrangement of steam-valve and ports both ports are partially open for a brief time during the period when one cylinder is full and the other almost empty, whereby there is no break in the column of water delivered. In other words, the pump is thereby made to deliver a uniform continuous stream as distinguished from an intermitting or pulsating stream.

As in other pumps of the class, it is desirable to admit a small quantity of air above the water to separate the steam and water, and for this purpose small valved petcocks are provided in the upper ends of the pump-cylinders, and where large cylinders are employed the effect of the partitions at the upper ends is found highly desirable in that the surface of the water is broken up into small areas, each of which will become calm almost instantly, whereas a larger surface would remain agitated for a relatively long period, not only condensing a large quantity of steam, but preventing the correct working of the apparatus, difficulties which are well recognized by those skilled in handling pumps of this character.

Having thus described my invention, what I claim as new, and desire to secure by Letters Patent, is—

1. A steam vacuum-pump embodying a duplicity of cylinders formed in an integral casting joined at one end only of the cylinders, said cylinders being free to contact and expand lengthwise independently, a connection between the opposite ends of the cylinders embodying rigid parts having flexible joints and valve mechanism on one of said rigid parts; substantially as described. 70

2. A steam vacuum-pump embodying a duplicity of parallel cylinders formed in an integral casting joined at one end only of the cylinders, an eduction-passage in the connecting portion of the casting, a connection between the opposite ends of the cylinders forming a steam-supply embodying rigid parts, a valve mechanism mounted on one of said parts and flexible joints interposed between said parts; substantially as described. 75

3. In a steam vacuum-pump, a duplicity of cylinders rigidly connected directly together at one end and a connection between the opposite ends embodying rigid parts, a valve mechanism on one of said parts and flexible joints between said parts; substantially as described. 85

4. A steam vacuum-pump embodying a duplicity of cylinders rigidly connected directly together at one end, induction and eduction ports in the connecting portion with independent valves between said ports and the cylinders, a rigid steam-supply fitting, between the opposite ends of the cylinders flexible joints between said fitting and cylinder and valve mechanism controlling the supply of steam to said cylinders mounted in said rigid fitting; substantially as described. 95

5. In a steam vacuum-pump, the combination with the twin cylinders rigidly connected directly together at the bottom, a suction-chamber formed separate from but extending beneath both said cylinders and a discharge-chamber above the level of the suction-chamber, of independent valves between the cylinders and suction and discharge chambers respectively, a steam-supply duct at the upper ends of the cylinders and valve mechanism controlling said steam-supply; substantially as described. 105

6. In a steam vacuum-pump, the combination with the cylinder having the steam-induction duct at the top and valve controlling the admission of steam, of the water-duct at the bottom of the cylinder, a valve-seat in said port, a bolt for holding said seat in position located on the opposite side of said seat from the valve and passing through to the exterior of the pump-wall, a valve co-operating with said seat and a retainer for the valve passing through the valve and supported by the seat; substantially as described. 115

7. In a steam vacuum-pump, the combination with the cylinders having the induction and eduction ports at the bottom, and the steam-ducts at the top with a valve control- 120

ling the admission of steam, of the grids secured in the induction and eduction ports at the bottom of the cylinders, bolts for securing said grids passing through to the exterior 5 of the pump-wall, valves seating on said grids on the sides opposite the said bolts, retainers passing through the valves into the grids to retain the valves in place and springs interposed between the heads of the retainers and 10 valves; substantially as described.

8. In a steam vacuum-pump, the combination with the cylinder having valved water induction and eduction ports at the bottom, of a steam-duct leading to the top of the cylinder, a valve in said duct, an engine connected with the valve for driving the same, a steam-pipe leading from the duct above the valve to the engine, and a valved exhaust-pipe leading from the engine; substantially as described. 15

9. In a steam vacuum-pump, the combination with the cylinder having valved water induction and eduction ports at the bottom and a steam-duct leading to the top of the cylinder, of a valve in said duct, an engine having a crank-shaft extended into the valve-chamber for operating the valve and steam supply and exhaust ducts for the engine; substantially as described. 25

30 10. In a steam vacuum-pump, the combination with the cylinder having valved water induction and eduction ports at the bottom and a steam-duct leading to the top of the cylinder, of a valve-fitting forming a part of said steam-duct, a valve in said fitting controlling the flow of steam, an engine for driving the valve and gearing between the engine-shaft and valve located in the steam-space of the fitting; substantially as described. 35

40 11. In a steam vacuum-pump, the combination with the cylinder having valved water induction and eduction ports at the bottom and a steam-duct leading to the top of the cylinder, of a valve-fitting forming a part of said steam-duct, a valve in said fitting controlling the flow of steam, an engine having its casing secured to the fitting, the crank-shaft of the engine extending into the fitting and forming the axis for the valve and gearing between 45 the valve and shaft located in the steam-space of the fitting; substantially as described. 50

12. In a steam vacuum-pump, the combination with the pump-cylinder, steam-duct leading thereto and valve-fitting interposed in said duct, of a valve in said fitting, an engine for driving the valve having a crank-shaft extending into the fitting, the said shaft being located in the live-steam space of the engine; substantially as described. 55

60 13. In a steam vacuum-pump, the combination with the pump-cylinder, steam-duct leading thereto and valve-fitting interposed in said duct, of a valve in said fitting, a multiple-cylinder engine for driving the valve the engine-shaft forming the journal for the valve and

gearing interposed between the shaft and valve; substantially as described.

14. In a steam vacuum-pump, the combination with the cylinders and a steam-duct having branches extending into both the cylinders, of a valve controlling the passage of steam through the branches of the duct, said valve being so proportioned that the branches of the duct are open simultaneously during a portion of the movement of the valve and 75 means for operating the valve; substantially as described.

15. In a steam vacuum-pump, the combination with the cylinders and a steam-duct having branches extending into both the cylinders, of a valve controlling the passage of steam through the branches of the duct, said valve being proportioned to admit steam to both said branches simultaneously throughout a portion of its movement and an engine 85 coupled with said valve for moving the same; substantially as described. 80

16. In a steam vacuum-pump, the combination with the cylinders, a steam-duct and branch ducts leading therefrom to the cylinders, of a flat rotary valve controlling the admission of steam to the branch ducts, located in the duct and held to its seat by steam-pressure, an engine for rotating said valve and means for effecting condensation of the steam 95 in the cylinders when the branch duct leading thereto is closed by the valve; substantially as described. 90

17. In a steam vacuum-pump, the combination with the cylinders, a steam-duct and branch ducts leading therefrom to the cylinders, of a flat rotary valve controlling the admission of steam to the branch ducts, located in the duct and held to its seat by steam-pressure, an engine having a crank-shaft forming 105 the journal of the valve, gearing between the valve and shaft located in the duct and means for effecting condensation of the steam in the cylinders when the branch duct leading thereto is closed by the valve; substantially as described. 110

18. In a steam vacuum-pump, the combination with the cylinder water induction and eduction ducts therefor and steam-induction duct, of the valve controlling the passage of steam through the said duct, an engine for driving said valve and an exhaust-duct leading from the engine to the water-induction duct; substantially as described. 115

19. In a steam vacuum-pump, the combination with the cylinders, induction-chamber from which water passes to both cylinders, steam-duct and valve controlling the passage of steam therethrough, of an engine for driving the valve and an exhaust-duct leading 120 from the engine to the induction-chamber; substantially as described.

20. In a steam vacuum-pump, the combination with the parallel cylinders, induction-chamber between said cylinders at the bottom 125 130

and steam-duct between said cylinders at the top, of a valve controlling the steam-duct and an engine for driving said valve, an exhaust-pipe having a valve therein and extending from the engine down between the cylinders to the induction-chamber; substantially as described.

21. In a steam vacuum-pump, the combination with the cylinder water induction and eduction ducts, steam - induction duct and means for controlling the admission and condensation of steam to effect inspiration and expiration of the water, of partitions in the cylinder for reducing the unbroken surface area of the water; substantially as described.

22. In a steam vacuum-pump, the combination with the cylinder, water induction and eduction ducts, steam - induction duct and means for controlling the admission and condensation of steam to effect inspiration and expiration of the water, of vertically-arranged partitions at the upper end of the cylinder for reducing the unbroken surface area of the water; substantially as described.

23. In a steam vacuum-pump, the combination with the cylinder having the reduced upper end, water induction and eduction ducts, steam-induction duct and means for controlling the admission and condensation of steam to effect inspiration and expiration of the water, of vertically-arranged partitions in the reduced end of the cylinder; substantially as described.

24. In a steam vacuum-pump, the combination with the cylinder having the reduced upper end, the steam-duct leading into the said reduced end and the baffle-plate for distributing the steam in said reduced end, of a valve controlling the admission of steam through the duct, an engine for operating said

valve means for effecting condensation of steam in the cylinder, and water induction and eduction ducts; substantially as described.

25. In a steam vacuum-pump, the combination with the cylinder having the tapered upper end, the steam-duct leading into the apex of the tapered portion, the baffle-plate for distributing the steam in the tapered end and the partitions for reducing the unbroken surface area of the water in said end, of a valve controlling the admission of steam through the duct, means for operating the valve, means for effecting condensation of steam in the cylinder, and water induction and eduction ducts; substantially as described. 55

26. In a steam vacuum-pump, the combination with the parallel cylinders, steam-duct and branch ducts leading to the cylinders, of joints interposed in said branch ducts to permit of independent expansion and contraction of the cylinders, a valve and engine for operating the same located at the junction of the main and branch ducts and water induction and eduction ducts for the cylinders; substantially as described. 60

27. In a steam vacuum-pump, the combination with the parallel cylinders, steam-duct and branch ducts leading to the cylinders, of joints interposed in said branch ducts embodying nipples and sockets therefor with means 70 for holding the nipples in the sockets, a valve and engine for operating the same located at the junction of the main and branch ducts, and water induction and eduction ducts for the cylinders; substantially as described.

ROBERT BRUCE EMERSON.
